Fig. 11.

Fig. 12.

Fig. 13.

FIG. 1 is an isometric view of a confection forming mold showing my new design;

FIG. 2 is a rear elevational view of the confection forming mold shown in FIG. 1;

FIG. 3 is a side elevational view thereof as seen from the left of FIG. 1, the side opposite thereto being a mirror image thereof;

FIG. 4 is a bottom plan view thereof;

FIG. 5 is an isometric view of the second embodiment of the confection forming mold shown in FIG. 1, wherein the convex ear has been placed in the middle of both sides;

FIG. 6 is a side elevational view of the mold shown in FIG. 5;

FIG. 7 is a bottom plan view of the mold shown in FIGS. 5 and 6;

FIG. 8 is an isometric view of a third embodiment of the confection forming mold shown in FIG. 1 having convex ears on all four corners;

FIG. 9 is a side elevational view of the mold shown in FIG. 8;

FIG. 10 is a bottom plan view of the mold shown in FIGS. 8 and 9;

FIG. 11 is an isometric view of a fourth embodiment of the confection forming mold shown in FIG. 1 having convex ears on all four corners and in the middle of the two opposite sides;

FIG. 12 is a side elevational view of the mold shown in FIG. 11;

FIG. 13 is a bottom plan view of the mold shown in FIGS. 11 and 12.

This is a continuation-in-part of design application Serial No. 4,868, filed November 30, 1966, now abandoned.

I claim:

The ornamental design for a confection forming mold, substantially as shown and described.
